Patented Oct. 24, 1922.

2 SHEETS—SHEET 2.

Inventor:
George Watson
By his Attorney,
Frederick Wright

UNITED STATES PATENT OFFICE.

GEORGE WATSON, OF LONDON, ENGLAND.

FURNACE FOR THE DESTRUCTION OF HOUSE AND GARDEN REFUSE.

Application filed March 10, 1920. Serial No. 364,611.

To all whom it may concern:

Be it known that I, GEORGE WATSON, a subject of the King of Great Britain, residing at Walter House, Bedford Street, 5 Strand, London, England, have invented new and useful Improvements in Furnaces for the Destruction of House and Garden Refuse, of which the following is a specification.

10 This invention relates to the construction of comparatively small furnaces, especially adapted for working under natural draught conditions and suitable for burning the refuse of gardens and houses.

15 The furnace consists of an outer casing of suitable material, such as, for instance, cast or wrought iron or steel, and it may if desired be lined with firebricks.

According to this invention in order to 20 provide a rigid structure the furnace is formed triangular in cross section and preferably tapers so that the capacity of the furnace is larger at the bottom than at the top in order to facilitate the falling of 25 the material within the furnace. The furnace space is enclosed by three plates which are secured together by angle pieces of suitable material, such as, for instance, cast iron, and preferably extend along the whole 30 length of the joint from top to bottom. Two sets of girdles or ties pass through the angle pieces and are secured to them by screw nuts by means of which the furnace is held together.

35 Asbestos or slag wool packing or cement or mortar of any kind may be used between the angle pieces and the edges of the plates to make the joints tight. The top casting, which is provided with a lid and a lever 40 for opening the same, is of ordinary construction. A chimney may lead from one corner of the furnace and a hanging bridge is provided near to the chimney opening inside the furnace for the purpose of causing 45 the smell and smoke from any refuse newly charged to pass downward through or over the hottest part of the fire thus minimizing the smoke and smell escaping from the chimney. It also causes combustion 50 to spread throughout the whole mass of refuse. The hanging bridge may be formed either of cast iron or of firebrick with a bar or bolt passing through it, and may be hung from the top casting by passing the 55 bolt through the same and supporting it

either by means of a nut or a cotter. The chimney may be carried through the top forming a hanging bridge.

Three draught openings are provided at the bottom of the furnace, one in each of the three sides, and plain plate doors are provided for wholly or partially closing the same, so that the draught may be easily regulated, taking advantage of the direction of the wind.

65 The furnace may be used either with or without a grate. When used without a grate the plates stand either on the earth or on a concrete or other smooth platform upon which the material to be destroyed lies while 70 it is being burned. In cases, however, where a grate is used, it is constructed of one casting with three legs and is placed in position on the ground, the furnace being erected over it. To facilitate the raking both above 75 and below the grate, the grate is made of such a height as to leave about half the rake door opening above it and half below it.

80 A plain hearth of brick concrete or earth is preferably used for the production of a manorial ash from the refuse, whereas the use of a grate is preferably when it is desired to produce a hard clinker instead of an ash.

85 The accompanying drawings show furnaces made in accordance with this invention. Figure 1 is an elevation, Figure 2 a section, Figure 3 a plan of one form of furnace; Figure 4 is a section and Figure 5 a plan of a grate suitable for use therein; 90 Figure 6 is a section and Figure 7 a plan of a modified form; and Figures 8 and 9 are similar views of another modification.

95 The furnace is formed of three plates *a* secured together by angle pieces *b*, whilst two sets of ties *c* and *d* are secured to them by nuts *c'* and *d'*, by which the furnace is held together. A chimney *e* of triangular section leads from one corner and below the chimney is a hanging bridge *f* which 100 is hung from the top by a bolt *f'*. Three draught openings *g* are provided at the bottom of the sides, each having a door *h* by which it can be wholly or partially closed, so that the draught may be easily regulated, 105 advantage being taken of the direction of the wind. The grate *j* is mounted on three legs *k*.

110 In Figures 6 and 7, the furnace is of similar construction to that shown in the for-

mer figures, except that the hanging bridge f^6 is made in one piece with the chimney e^6 . The chimney e^6 fits into the hole provided for it and has flanges e^1 which rest on the top of the furnace.

When the part of the chimney exposed to the greatest heat is burnt away the chimney may be turned exposing another of the sides to the greatest heat.

10. In the furnace shown in Figures 8 and 9, the chimney e^8 is of the same size as the top of the furnace, and in this case the hanging bridge is necessarily dispensed with.

By constructing the furnace of a triangle 15 form the plates employed form a rigid structure as soon as they are tightened by the tie bolts. With a square construction this is not the case as the plates would fall inwards unless snugs were placed upon them 20 to prevent it. By using three plates I avoid the necessity of a base plate to give rigidity to the structure and the construction conveniently adapts itself to the use of a chimney with a feed opening in front of it. 25 As before stated the advantage of the hanging bridge or chimney projecting into the furnace is that it causes the smell or smoke from any refuse newly charged to pass downward through or over the hottest part 30 of the fire thus minimizing the smoke or smell escaping from the chimney. It also causes the combustion to spread throughout the whole mass of refuse.

What I claim is:—

- 35 1. A furnace for the destruction of refuse in which the body of the furnace consists of three plates secured together by three

angle pieces at the corners and ties connecting the angle pieces and secured thereto.

2. A furnace for the destruction of refuse 40 in which the body of the furnace consists of three plates secured together by three angle pieces at the edges and ties connecting the angle pieces and secured thereto, each of said plates being formed with a 45 draft opening near the bottom.

3. A furnace for the destruction of refuse, of triangular cross section and of larger cross section at the bottom than at the top, and which has a chimney of triangular 50 cross section formed in one piece with a hanging bridge.

4. A furnace for the destruction of refuse, of triangular cross section, having a chimney of triangular cross section which extends 55 through the top of the furnace and is provided with a hanging bridge.

5. A furnace for the destruction of refuse, of triangular cross section and of larger cross section at the bottom than at the top, 60 having a chimney of triangular cross section which extends through the top of the furnace and is provided with a hanging bridge.

6. A furnace for the destruction of refuse, of triangular section throughout and having 65 a chimney secured to the narrowest part of the top of the furnace which extends through the top of the furnace and is provided with a hanging bridge.

In testimony that I claim the foregoing 70 as my invention I have signed my name this 23d day of February, A. D. 1920.

GEORGE WATSON.
